UNITED STATES PATENT OFFICE

MATHIAS MAMBOURG, OF LUXEMBURG, LUXEMBURG

SHEET-METAL PILE UNIT

Application filed November 17, 1927, Serial No. 233,992, and in Germany November 23, 1926.

The present invention relates to metal piling, and more particularly to piling which is built up of a multiplicity of interlocking sheet metal sections or units; its object being the provision of an improved unit of the character indicated so constructed as to avoid various defects inherent in the units heretofore employed while, at the same time, possessing certain advantageous features of its own.

It has been attempted in the past to roll metal sheets to form the pile sections or units without regard to the distribution of the metal, which naturally resulted in waste and lack of economy in material because the finished articles were not always satisfactory as to resistance, water-tightness, etc.; consideration being paid for the most part solely to the requirements of the rolling operation. Experiments were made in constructing both low and high forms of sections in various ways to improve the resistance as well as the facility of rolling, while avoiding secondary strains in the metal and too rapid cooling thereof; but such experiments likewise have not been commercially successful. Finally, difficulties have been experienced in connection with the joint by means of which adjacent sections or units are interlocked; such difficulties involving not only the formation or rolling of the joints but also their maintenance in water-tight condition.

My invention eliminates all these defects by constructing a section or unit having a special shape which permits it to be rolled easily and to possess the desired resistance, and which also results in the production of constantly-tight joints.

The single figure of the accompanying drawing is a horizontal cross-sectional view of one of the improved pile units of the invention, with portions of the two immediately-adjacent units interlocked therewith.

As shown in said drawing, the pile section or unit consists of an intermediate portion or web and two end portions or wings. The web, indicated at *a*, occupies a slanting position in the unit, and the two wings are integral with it, each wing embodying two branches or members *b* and *c* arranged at

right-angles to each other. The inner branches *b* of the two wings are disposed perpendicularly to the neutral axis of a series of pile sections or units taken in horizontal section, while the outer branches *c* are parallel with said axis. The web *a* is thinner than the inner wing branches *b*, and the latter, in turn, are slightly thinner than the outer branches *c*, and the slant of the said web is such that it is disposed at an obtuse angle both to the branches *b* as well as to the direction in which the branches *c* extend, as is clearly shown.

The successive units or sections are designed to be connected in interlock by means of joints which are somewhat analogous to ball-and-socket joints; and in the construction illustrated (which is not essentially limitative) the two members *d* and *e* corresponding, respectively, to the socket and ball members of such joints are provided one on one end and the other on the other end of each unit. Both members are of special construction, and both are essentially resilient or elastic to some degree. The socket member *d* has the form of a crescent, and the companion or complementary member *e* is also crescent-shaped but is of smaller size or diameter, such shaping producing the desired resilience; but the two members are of opposite concavity so that the horns, so to speak, of the socket will extend over and oppositely to those of the inner head or member.

Due to this shaping and interfit of the two members, they will constantly maintain the desired tightness, while their initial positioning and jointing can be readily and quickly effected. The rigidity of the unit is increased by providing the right-angular wings at the ends of the web, and the resistance is extremely high in proportion to the amount of metal used. Finally, the rolling operation can be carried out regularly and at high speed, thus avoiding waste and reducing production costs.

I claim as my invention:

A sheet metal pile unit, comprising an intermediate web portion which occupies a slanting position in the unit; and two wings integral with the web and located at the ends

thereof and each shaped to form a right dihedral angle; said web being inclined at an obtuse angle to the inner branches of the wings and to the direction in which the outer branches of said wings extend.

5 In testimony whereof he affixes his signature.

MATHIAS MAMBOURG.
